UNITED STATES PATENT OFFICE.

EDWARD REUKAUF, JR., OF PHILADELPHIA, PENNSYLVANIA, ASSIGNOR TO CAREY-McFALL CO., OF PHILADELPHIA, PENNSYLVANIA, A CORPORATION OF PENNSYLVANIA.

MEANS FOR SECURING DRAW STICKS IN WINDOW SHADES.

Application filed January 19, 1928. Serial No. 247,862.

This invention relates to means for securing the draw-sticks in the hems of window shades, especially those used in automobiles of the various enclosed types or similar vehicles. The common practice for securing these sticks in place is to fold the curtain material over the respective ends of the stick and manually sew the adjacent edges together to close the ends of the hem of the curtain, and thereby retain the stick within the said hem. A screw eye is then placed in each end of the stick for the accommodation of the guide rods or wires extending parallel to the longitudinal edges of the curtain, which prevent the curtain from flapping in the wind when the vehicle is in motion.

The object of my invention is to eliminate the manual sewing operation, which takes time, and to secure the stick in place within the hem of the curtain solely by the said screw eyes and end plates interposed between the eye and the shade material, thereby reducing the cost of production per shade, increasing the production of any given number of operators, and materially improving the appearance of the finished article.

The invention will be hereinafter described in detail, reference being had to the accompanying drawings, of which:

Fig. 1 is a detached perspective view of the curtain elements;

Fig. 2 is a perspective view of the curtain with the elements assembled;

Fig. 3 is a sectional view on the line 3—3 of Fig. 2;

Fig. 4 is a perspective view of a modified form of a detail of the curtain assemblage.

In the drawing, the curtain proper is illustrated and indicated by the reference character 1, the edges of which may or may not be turned back upon the curtain and sewed in place as indicated at 2 and 3 respectively, as desired.

Extending transversely across the end of the curtain is a stick-retaining hem 4 which is formed by folding the curtain material upon itself and securing the edge thereof to the body 1 by a line of stitches 3^a.

A draw-stick 5 is adapted to be placed in the hem 4, after which the curtain material at the ends of the hem 4 is folded over the respective ends of the draw-stick 5 as indicated at 6 and 7.

The draw-stick 5 is provided with a pre-formed aperture 8 at each of its ends for the reception of the threaded shank 9 of a screw-eye 10.

After the curtain material is folded over one end of the stick 5 as indicated at 6 and 7, a washer or end plate 11 is placed on the shank 9 of the screw-eye 10 and the said shank forced through the folds or flaps of curtain material and into the aperture 8 in the end of the draw-stick 5, the screw-eye 10 being simultaneously rotated to cause the threads of its shank 9 to take hold in the walls of said aperture and thereby secure the screw-eye 10 in place, the said screw-eye pressing the end plate 11 into rigid engagement with the overlapping portions 6 and 7 of the curtain material and these portions into rigid contact with the ends of the stick 5, thereby efficiently securing the whole of the assemblage together and preventing the stick from moving relative to the said curtain. This operation is then repeated at the other longitudinal edge of the curtain.

Rotation of the screw-eye 10 is preferably effected by power driven means which also adds to the speed of production, and the performing of the aperture 8 in the end of the stick obviates the possibility of the stick being split by the rapid insertion of the screw-eye shank.

Obviously the washer or end plate 11 may be replaced by an end plate such as that illustrated in Fig. 4 and indicated by the reference character 11^a which is of the same general contour as the end of the stick 5 and which will entirely conceal the overlapping portions 6 and 7 of the curtain when assembled.

Obviously if the shade is not to be used in conjunction with guide rods or wires, the screw-eye may be replaced by an ordinary headed screw or a tack or nail having a head which will prevent the laps 6 and 7 from slipping off the outer end of such a retaining element.

I claim:

1. In combination with a window shade having a hem formed therein and a draw-stick located in said hem, means for securing the draw-stick in said hem comprising a flap formed by folding the shade material over the end of the draw-stick; a retaining element adapted to be passed through said

flap and to be secured in said draw-stick for securing the flap in place.

2. In combination with a window shade having a hem formed therein and a draw-stick located in said hem, means for securing the draw-stick in said hem comprising a flap formed by folding the shade material over the end of the draw-stick; a retaining element adapted to be passed through said flap and to be secured in said draw-stick; and a head on said retaining element adapted to engage and hold said flap in place.

3. In combination with a window shade having a hem formed therein and a draw-stick located in said hem, means for securing the draw-stick in said hem comprising a flap formed by folding the shade material over the end of the draw-stick; a retaining element adapted to be passed through said flap and to be secured in said draw-stick; an end plate on said retaining element engaging the flap; and a head on said retaining element engaging said end plate for securing the whole as a rigid assemblage.

4. In combination with a window shade having a hem formed therein and a draw-stick located in said hem, means for securing the draw-stick in said hem comprising a pair of overlapping flaps extending over the end of the draw-stick from the opposite sides of said hem and formed by folding the shade material lying adjacent the end of said draw-stick thereover; a retaining element adapted to be passed through the said flaps and to be secured in said draw-stick and a head on said retaining element adapted to engage the flaps and secure them to the end

of said stick, whereby the stick is secured in the said hem.

5. In combination with a window shade having a hem formed therein and a draw-stick located in said hem, means for securing the draw-stick in said hem comprising a pair of overlapping flaps extending over the end of the draw-stick from the opposite sides of said hem and formed by folding the shade material lying adjacent the end of said draw-stick thereover; an end plate adjacent the flaps; a retaining element adapted to be passed through the end plate, through the flaps and to be secured in the said stick; and a head on said securing element adapted to engage said end plate for securing the whole as a rigid assemblage.

6. In combination with a window shade having a hem formed therein and a draw-stick located in said hem, means for securing the draw-stick in said hem comprising a pair of overlapping flaps extending over the end of the draw-stick from the opposite sides of said hem and formed by folding the shade material lying adjacent the end of said draw-stick thereover; an end plate adjacent the outermost of the overlapping flaps; and a screw-eye adapted to pass through an aperture formed in said end plate, through the pair of overlapping flaps and into the end of said draw-stick, the annular head of said screw-eye pressing against the said end plate which presses the flaps into contact with the end of the draw-stick, for securing the draw-stick in place in said hem.

EDWARD REUKAUF, Jr.
